AUTOMATIC STATION SELECTOR FOR
RADIO RECEIVERS

Oscar A. Carlson and Louis Pratt, Detroit, Mich.

Application August 6, 1934, Serial No. 738,756

11 Claims. (Cl. 250—20)

The object of the invention is to provide a station selector for use in connection with radio receiving sets that will make possible the automatic tuning or turning on of the receiver for 5 one or more selected programs broadcast at specified times; to provide a selector which may be incorporated in conventional sets and initially adjusted to resonance with the stations to be automatically tuned in and which will 10 thereafter need no further adjustment except to selectively provide for the automatic operation of certain stations when and as desired; to provide an automatic control in which the setting for automatic operation may be accomplished 15 with a minimum of care and skill on the part of the operator; to provide such a control in which means is incorporated for automatically or manually rendering the automatic switching-in or turning-on means inert; to provide a 20 mechanism of the kind indicated in which the element variable for resonance, whether a capacity, an inductance, or both, is positively connected in circuit with a minimum of likelihood of an increase or diminution of the capacity or 25 inductance required; to provide a station selector in which is incorporated a time mechanism with which the selecting mechanism is synchronized; and generally to provide an apparatus for the 30 indicated purpose which, for the functions to be performed, is of comparatively simple form and susceptible of comparatively cheap manufacture.

With this object in view, the invention consists in a construction and combination of parts of which a preferred embodiment is illustrated in 35 the accompanying drawings, wherein:

Figure 1 is a view partly in side elevation and partly in section of an automatically actuated variable capacity with which the invention is incorporated.

Figure 2 is a sectional view on the plane indicated by the line 2—2 of Figure 1.

Figure 3 is a front elevational view of the dial and switch actuating setting means.

Figure 4 is a sectional view on the plane indicated by the line 4—4 of Figure 2.

Figure 5 is a sectional view on the plane indicated by the line 5—5 of Figure 23.

Figure 6 is a detail elevational view of the structure of Figure 23, looking from the left.

Figure 7 is a sectional view on the plane indicated by the line 7—7 of Figure 5.

Figure 8 is a sectional view on the plane indicated by the line 8—8 of Figure 22.

Figure 9 is a sectional view on the plane indicated by the line 9—9 of Figure 1.

Figure 10 is a detail plan view of the switch-actuating pin-returning cam and an adjacent portion of the pin carrying disk.

Figure 11 is a sectional view on the plane indicated by the line 11—11 of Figure 1.

Figure 12 is a sectional view similar to Figure 11 but showing the position of the parts in the initial step of adjusting the member variable to bring the receiver into resonance and in this case the condenser.

Figure 13 is a view similar to Figure 11 but showing the position of the parts with the condenser in the position of minimum capacity, which will ordinarily be its position when the set is not in use.

Figure 14 is a view, partly in plan and partly in section, of the magnet control switch and its actuating bar, the former being shown in open position and the bar in its extreme position of movement in one direction.

Figure 15 is a view similar to Figure 14 but showing the magnet control switch in closed position and the actuating bar in its extreme position of movement in the opposite direction.

Figure 16 is a view similar to Figure 14 but showing the switch actuating bar in its intermediate position.

Figure 17 is a view partly in plan and partly in section of the detent quick-return spring and its mounting, showing the spring when the detent is in its release position.

Figure 18 is a view similar to Figure 17 but showing the position of the spring when the detent is in its restraining position.

Figure 19 is an elevational view of one of the several detent abutment stops.

Figure 20 is an enlarged detail sectional view of the manual resetting shaft for the time mechanism.

Figure 21 is a diagrammatic view of the control circuits for the actuating magnets.

Figure 22 is a sectional view similar to Figure 21 but showing the position of the parts in the pin setting operation.

Figure 23 is a detail plan view of a set of the complement busbar switches with an adjusted switch actuating pin in position to actuate one of the same.

While the invention may be employed to vary either the capacity, or inductance, or both if they are so mounted that a single movement will effect the proper adjustment, but since it is generally the custom to tune the receiver by varying the capacity, the invention is illustrated as constituting the adjusting means for the variable

condenser 30, on the shaft of which is mounted a double sheave 31 comprising the sheave elements 31a and 31b. These sheave elements constitute the means by which the reciprocatory movement of the plungers of the solenoids 32 and 33 may be translated into rotary movement, the core of the plunger 32 having a flexible member 34 trained around the sheave 31b and the core of the solenoid 32 having a flexible member 35 trained around the sheave element 31a but in the opposite direction from that in which the flexible element 34 passes around the sheave element 31b. The flexible elements are terminally anchored to the sheave and when one solenoid is active, its flexible element is unwound from its sheave but the flexible element of the other sheave element is reeled thereon. When the other magnet is active, the reverse is true. Thus, by energizing one solenoid the condenser is adjusted to maximum capacity whereas by energizing the other solenoid it is adjusted to minimum capacity. But the mechanism provides for adjustment of the capacity in any amount within the range of the condenser.

To provide against sudden or intermittent movement being imparted to the rotary member of the condenser, the shaft carries a spur gear 36 meshing with the pinion 37 mounted in common with the spur gear 38, the spur gear 38 meshing with the pinion 39 on the shaft of a fan 40, the fan shaft and the shaft of the gear and pinion 37 being mounted in an appropriate bracket 41 secured to the condenser 30.

Attached to the hub of the double or dual sheave 31 is a disk 42, this disk constituting the means by which various increments of capacity are secured. The disk is formed with series of holes 43 and 44, the holes 43 having the same angular spacing as the holes 44 and both series 40 extending for a distance of slightly more than 180°. The holes are formed near the periphery of the disk and constitute the means for the attachment of the stops 45, each of which is mounted at a selected point on the disk where the detent 46 may engage it when the movable element of the condenser is in the proper position to give the desired capacity for a selected station. Each stop 45 is formed with a hole 47 through which a screw passes and threadingly engages one of the holes 43. A similar screw is employed to engage the companion hole 44 but this screw passes through an arcuate slot 48, this slot being formed on a curve of which the center of the hole 47 is the center. The slot 48 opens at one side of the stop. Thus when the stop is mounted on the disk, it may be swung with the screw in the hole 47 as a pivot which will vary the position of that end protruding beyond the edge of the disk circumferentially of the disk. In this way, when the 50 movable element of the condenser is set for the exact capacity desired, the stop 45 may be brought to position where, when the angular end of the detent 46 is engaged in the crotch between the longer and shorter horns 49 and 50, the securing 55 screws may be tightened. Thereafter, whenever the detent is brought into a position of obstruction to the longer horn, the variable element of the condenser will be stopped and the condenser thus set to the proper capacity of the selected 60 station.

In the illustrated embodiment of the invention, it is shown arranged to select any one of five stations—that is, the range of the illustrated embodiment is five stations, which may be any five 65 within the broadcast range by the selection of

the proper holes in the series 43 and series 44 at which are mounted the stops 45. A terminal stop 45a is mounted at one end of the series of holes, this stop being longer than the stops 49 but similarly engaged with the detent 46, not only to lock the condenser in the position of minimum capacity but to retain the detent in a different position from that it occupies when engaging the stops 45. This for a purpose hereinafter appearing. Since the stop 45a is the terminal stop, a 10 hole for the mounting screw in the series 44 is substituted for the arcuate slot 48, since no nice adjustment of this particular stop is necessary. Concentric with the disk 42 is an arcuate rack 51 formed with a series of holes 52 of the same angular spacing as the holes 43 and 44. These holes 52 serve as the mounting means for the stationary elements 53 of circuit closers, of which the movable element is in the form of a pin 54 projecting through a swivelly mounted post 55 15 mounted on the plate 56 which is carried by the disk 42. A spring 57 is tensioned between the inner end of the pin 54 and the remote end of the plate 56 and tends to keep the pin normally radially, so that in the rotation of the disk, as when 20 the movable element of the condenser is actuated, the pin will wipe the stationary elements 53. The elements 53 are in the form of inwardly-projecting radially-arranged pins and these are set in the various holes 51, according to the adjustments of 25 the stops 45 on the disk 42. This, so that when the pin 54 engages one of the elements 53, when other conditions are right, will effect stop engaging movement of the detent.

The detent 46 is rockably mounted in a bearing 35 35 and is formed with an arm 56 with the extremity of which a link 57 is engaged, this link being terminally connected with the core of a double-wound solenoid consisting of the windings 58 and 59 which are alternately energized. Thus 40 when the winding 58 is energized, the core will be elevated and the detent released from an engaged stop. When the winding 59 is energized, the downward movement imparted to the core will effect stop engaging movement of the detent. 45

The detent in addition to being provided with the arm 56 is formed with an additional pendent arm 60 which is pivotally connected, as at 61, with the switch actuating bar 62, the latter being preferably of non-conducting material but slidably mounted between the spring contacts 63 mounted upon but insulated from the frame 64. The spring contacts constitute the elements of the circuit closer for the control of the radio receiver, 50 that is, for the control of the energizing current for the receiver. The switch actuating bar has a metallic terminal 64 which, in one position of the bar, bridges the contact springs 63 and thereby closes the energizing circuit for the receiver. 55 60

The switch actuating bar 62, also engages the movable element of the switch 65, opening this switch in one position but permitting it to close when in the other position, the switch being of a form where it is yieldingly held in closed position. The switch 65 controls, in combination with other switches, hereinafter described, the circuits on the solenoids 32, 33, 58, and 59. When the bar is moved to its extreme position in one direction, it opens the switch 65 and bridges the 65 contacts 63 with the metallic terminal 64. In its extreme position in the other direction, the switch 65 is closed and the metallic terminal 64 is in a position where it does not bridge the contact springs 63. But the latter engage in the notches 70 75

66. The bar 62 has an intermediate position where it holds the switch 65 in open position without bridging the metallic terminal 64 with the contact springs 63. This intermediate position of the switch actuating bar obtains when the 5 detent 66 is engaged with the stop 45a, since this stop, being of a greater radial extent than the remaining stops, limits the inward movement of the detent and therefore limits that movement of the 10 switch actuating bar to a point which will prevent closure of the switch 65.

Detent movement is initially imparted by the solenoids 58 and 59 but since these solenoids are not maintained in circuit a sufficient length 15 of time to provide for the prescribed movement of the switch actuating bar 62, a mechanical means is employed to complete the movement once begun and this means consists of the spring 67 terminally anchored to the extremity of an 20 outturned plate 68 mounted at the end of a bracket arm 69 secured to the frame 64. Pivotally mounted on the bracket 69 on a pin 70 carried by the bracket and which in turn carries the plate 68, is a swinging arm or finger 71 to 25 which the other extremity of the spring 67 is anchored. The arm or finger 71 is provided with a pilot 72 which enters a slot 73 formed in the arm 60 of the detent. As the detent moves, therefore, and the arm 60 moves with it, the finger 71 is 30 caused to swing by reason of the pilot 72 engaging in the slot 73. After the arm has passed a point where its axis is in alignment with the axis of the plate 68, when the spring 67 is subject to its greatest tension, the spring collapses 35 on the opposite side and the initial movement imparted to the arm 60 is thus completed by the spring. This is the case, irrespective of the direction in which the arm 60 is moving, the latter moving in one direction in detent releasing 40 operation and in the other direction in the stop engaging operation of the detent.

The multiple pole circuit closer consisting of the finger 54 and the stationary elements 53 controls the detent latching solenoid 59 but does 45 this in conjunction with a plurality of switches disposed in spanning relation to the busbars 74 and 75, these busbars being mounted upon an insulating strip 76 carried by supporting studs 77. The switches consist of flat springs 78 bent into 50 U-shaped form, one leg of each being extended to provide a mounting means 79 by which the switch is secured to the strip 76. This arrangement disposes the free leg above the busbars from which it is normally spaced but into bridging 55 relation to which it may be moved by a spool spring 80 carried at the extremity of an actuating crank 81 pivotally mounted in the strip 76 and provided with an angular hand 82 engageable with an actuating pin hereinafter described. The 60 switches 78 are arranged in groups and are so positioned that the angular ends 82 of the cranks may be engaged by the switch actuating pins 83 which are carried by a disk 84 which is formed with a plurality of concentric circular series of holes of 65 which the corresponding holes in the different series are arranged in radial lines, so that individual holes in the different series are the same angular distance apart. The switch closing pins are mounted in these holes and they are frictionally held in either extended or retracted positions, the former effecting switch closing movement and the latter leaving them inactive so far as any switch closing function is concerned. The 70 frictional mounting of the pins is secured by making the disk 84 of laminar form, of which the 75

body portion consists of a relatively thick fiber lamina 84a secured to the outer face of which is a metallic lamina 84b, the latter securing in place a lamina 84c, preferably of soft rubber. The holes extend through all the laminae and 5 by reason of the compression of the lamina 84c by the lamina 84b, the material of the rubber lamina invades the holes in the other two laminae, so that it effects a peripheral gripping action on the pins and retains them in either of their set 10 positions.

The disk 84 is mounted on the extremity of a shaft 85 which is both angularly and axially movable in a tubular shaft 86 which is journaled in appropriate bearings formed in the spaced plates 15 87 which are also carried by the supporting studs 77. The tubular shaft at the end remote from the disk 84 carries a spur gear 88 from which a driving connection to the shaft 85 is effected through a yoke 89, the latter having arms of different lengths but formed with inturned terminals 90 which enter holes or openings formed in the gear. The yoke is secured to the shaft 85, as is also the turning dial 91, the dial being exposed at the front of the panel 92 with which the 20 supporting studs 77 are connected. By making the arms of the yoke of different lengths, there is but one position of the yoke with respect to the gear that will permit interlocking of the yoke and gear and there is thus provided a releasable 25 connection between the shaft 85 and tubular shaft 86, which, after release, may be established when only the proper relation obtains between the dial and gear 90. This because a timed relation must be maintained between the time control mechanism hereinafter described, the dial and the disk 84.

Pin setting operation is accomplished through the instrumentality of plungers 93, 94, 95, 96, 97, and 98, these plungers being of varying lengths 40 and being arranged in two series, one on each side of the dial. The plungers are of varying lengths to provide for effective finger operation—that is, so the finger may be readily engaged with any one to the exclusion of the others. The 45 plungers are slidably mounted in the panel 92 and in the plates 87, being reduced in diameter between the plates and surrounded by compression springs 99 to keep them normally extended. The inner third and fifth series of pins are actuated by the plungers 96, 97, and 98 and the second, fourth and outer series of pins by the plungers 95, 94, and 93, the latter plungers being directly behind the pins but the former plungers having their pin actuating heads mounted on 50 laterally disposed stems 100. This obviously so that the plungers may be symmetrically disposed on opposite sides of the dial. When the pins are in their retracted or inoperative positions and the yoke is engaged with the gear 88, the pins are 55 without the range of movement of the plungers but when it is desired to project a pin, the yoke 89 is released from the gear 88 by an outward pull on the dial knob (Figure 22) when the disk 84 may be rotated by the dial knob to position 60 any desired pin behind a selected plunger and when the latter is pushed in, the pin directly behind it is projected through the disk, so that it will be in switch actuating position when the disk is returned to its normal position which will 65 be the case when the yoke is re-engaged with the gear. The dial provides for the proper positioning of a selected pin.

The compression spring 101 which is disposed 70 in surrounding relation to the tubular shaft 86, 75

- is compressed between the disk and the rear plate 81 and normally impels the disk in a direction away from the panel 92, so as to yieldably retain the yoke 88 in gear engaging position.
- 5 When it is desired to return projected pins to their inactive or inoperative positions, the disk is pulled forward as in the pin setting operation, and in this position the cross-sectionally angular pin return plate 102 may be brought in position 10 with the corner edge in close proximity to the back of the disk, when the rotation of the disk through the instrumentality of the dial knob will result in a wiping action on the pins that will force them forwardly and return them to their 15 inoperative positions in the disk. The pin returning plate is carried by an arm 103 pivotally mounted at 104 and formed with a forked extension 105 which straddles the plunger 106, the forks straddling a pin 107 inserted transversely 20 through the plunger 108. The plunger is yieldingly impelled forwardly by a compression spring 109, housed in a guide 110 in which the plunger is slidably mounted as well as in a slide bearing 111. The plunger extends from the front of the 25 panel and when pushed inwardly swings the pin returning plate forwardly to its position behind the disk, when the extension 105 abuts the forward face of the bearing 111 and it then acts as a limiting stop for the pin returning plate.
- 30 The time mechanism is electrically actuated, the actuating means being a motor 112, preferably synchronous and provided with a pinion 113 meshing with a spur gear 114 which is mounted in common with a pinion meshing with the spur gear 115. From the spur gear 115 motion is communicated to the spur gear 116, which drives the second spindle 111. The spur gear 115 has a pinion mounted in common with it by which motion is communicated to the gear 116 and the 35 gear 115 and its pinion are mounted on a sleeve 118 which is loosely mounted on a shaft 119. Keyed to the shaft 119 is a gear 120 which meshes with a pinion 121 mounted on the second spindle. Thus while rotation to the second spindle is communicated from the motor 112 through the gear train whose terminal element is 116, motion is 40 communicated from the second spindle to the minute spindle 122 through the pinion 121 and gear 120, so that angular or turning movement is imparted to the shaft and accordingly to the pinion 123 which meshes with the gear 124 mounted on the minute spindle. The gear 120 is formed with a hub circumferentially grooved to be engaged with one end of a shifter lever 125, this lever being fulcrumed on the bracket 126 and having its force arm forked to engage the pins of a thimble 127 which is mounted on the resetting shaft 128, the resetting shaft being mounted for both angular and axial movement and having a terminal finger knob 129. The thimble is impelled rearwardly in a direction away from the panel 92 by a compression spring 130, while the gear 120 is impelled forwardly or towards the panel 92 by a compression spring 131. If the shaft 128 be moved forwardly by pressure applied on the head 129, the gear 120 will be moved rearwardly along the shaft 119 and will thus be disengaged from the pinion 121, so that only the second spindle will be left for rotation by the 50 motor 112. This so that the time mechanism or clock may be set when necessary to do so. Motion to the hour spindle 132 is communicated from the minute spindle to the pinion 133, the gear 134 pinion 135 mounted in common with 55 the gear 134 and gear 136 carried by the hour

spindle. The gear 134 and pinion 135 are mounted on a hollow spindle 137 (Figure 20) to which they are secured, as is also the pinion 138, the latter meshing with a pinion 139 which in turn meshes with a pinion 140, the latter being 60 mounted on a common shaft with the spur gear 141 which meshes with the gear 88. By this arrangement, the disk 84 is driven in timed relation with the time mechanism, when the yoke has its interlocking connection with the gear as 10 is normally the case.

An on-and-off switch 142, spring impelled as indicated at 143, to open position, is latched in closed position by the pivotally mounted pawl 144, the latter having a tail portion 145 which, 15 when the pawl is in switch latching position, is in position to be engaged by a trip lug 146 mounted on the rear face of the gear 136. The on-and-off switch which controls the energizing circuit for the actuating magnets is designed for 20 actuation from the front of the panel 92, so that it may be moved to closed position when desired after having been released.

In the resetting operation of the time mechanism, the shaft 128 is moved forwardly by pressure applied to the turning knob 129. This rocks the shifter lever 125 and moves the gear 120 back out of mesh with the pinion 121. But the shaft 128 moving forwardly engages its key 147 with the key-way in the sleeve 137. Then rotation of 30 the shaft 128 will impart movement to the hour and minute spindles independent of the time mechanism and will also impart movement to the gear 88, so that the timed relation established between this gear and the minute and hour 35 spindles when the apparatus is originally constructed will not be disturbed. Thus the time mechanism can be set to the proper time.

Mounted on the rear of the frame 148 by which the various elements of the time mechanism are 40 carried is a disk 149 of insulating material, this disk being rotatably mounted on the disk 150 in common with a toothed wheel 151. This toothed wheel is formed with fifteen teeth which are successively engaged by the crank 152 formed at 45 the rear extremity of the second spindle. Each revolution of the second spindle, therefore, moves the toothed wheel the distance of one tooth, so that the wheel accomplishes one revolution every fifteen minutes. Bearing upon the periphery of 50 the disk 149 are drag arms 153 and 154 pivotally mounted in a bracket 155. Once in each revolution of the disk, these drag arms are engaged by the lug 156 carried by the disk and when so engaged function to operate each of its own switch, 55 the drag arm 154 controlling the switch or circuit closer 157 and the drag arm 153 controlling the switch or circuit closer 158. The fixed contacts of the circuit closers 157 and 158 are connected in common to one side of the energizing 60 circuit. The movable contact of the circuit closer 158 is connected through the switch 65 to one terminal of each of the solenoids 59 and 32. The remaining terminal of the solenoid 32 is connected in on the busbar 75 and the remaining terminal of the solenoid 59 is connected to the contact finger 65. The movable contact of the circuit closer 157 is connected to one terminal of the solenoids 58 70 and 33, whose other terminals are connected in on the busbar 75. The on-and-off switch 142 is interposed between the busbar 74 and the opposite side of the energizing circuit. The switches 78 are connected one each to its corresponding contact pin 58.

In the operation of the invention, the rotation 75

of the second spindle of the time mechanism results in intermittent rotation of the toothed wheel 151 and with it the disk 149. When the device is to be set to turn on the radio receiver for selected programs, the disk is moved forward as before explained and rotated to position the necessary switch actuating pins behind the pin setting plungers which are then pushed in to project the pins forward. If the desired pins have been set both for turning on and turning off the set, the disk is returned to its normal position, when the pins will be in the path of the angular ends of the actuating cranks of their respective switches 78. As the disk is advanced by the time mechanism, a pin will actuate a selected switch 78, bringing it into bridging relation to the busbars 74 and 75. The condenser at this time will be in the position of minimum capacity and the detent will be engaged with the stop 45a. When the lug 55 on the disk 149 engages the drag arm 154, it will close the circuit closer or switch 151 and current will then flow from the energizing circuit through the switch, over the conductor 159 to the solenoid 33, the busbar 75, across that switch 78 bridging the busbars to the busbar 74 and thence through the switch 142 back to the opposite side of the energizing circuit. But there will be no condenser movement imparted since the condenser is in the position of minimum capacity. However, current in the conductor 159 also passes through the solenoid 58 to the busbar 75 and thence across the switch 78 and back to the opposite side of the energizing circuit, resulting in raising the detent to releasing position which is accomplished in the manner heretofore described. But the traveling disk 149 carries the lug 156 into engagement with the drag arm 153, thus effecting closure of the circuit closer or switch 158. With the release of the detent, the switch 65 is closed as above explained and when the circuit closer 158 is closed, current flows from one side of the energizing circuit through the switch or circuit closer 158 and over the conductor 160 to the solenoid 32 and thence over the switch 78 and back to the opposite side of the energizing circuit over the same path as the current that energized the solenoid 33. But the solenoid 32 functions to advance the condenser to increase its capacity and when the contact pin 54 shall have engaged the fixed contact 53 connected with the switch 78 which has been engaged with the busbar, a circuit is established on the solenoid 59, current flowing from the conductor 160 through the solenoid 59 and thence over the conductor 161 to the contact pin 54 and thence to the fixed contact 53, conductor 162, the switch 79, the busbar 74 and thence back to the opposite side of the energizing circuit. The detent is then shifted into position to engage the proper stop 45 and latch the condenser in position for proper capacity for the selected station. But with the engagement of the detent with the stop, the switch 65 is opened, but the receiver control switch comprising a contact spring 63 and bridging member 64 is closed and the receiver is put in operation. After the prescribed interval, determined by the setting of the proper pin 83, the switch 79 previously operated to set the receiver in operation, is again actuated to cut the receiver out of circuit. On the second closing of the switch 79, the circuit closer 151 is first actuated by the lug 156 and the solenoids 58 and 33 are energized, the former releasing the detent and the latter returning the condenser to the position of minimum capacity. When the lug effects

later operation of the circuit closer 158, the solenoids 59 and 32 are energized, the former returning the detent to engagement with the stop 45a because the contact pin 54 is in engagement with the fixed contact 53a and there can be no movement of the condenser in the reverse direction because the pull exerted by the magnet 32 is arrested by the engagement of the detent with the stop 45a. As above explained, in connection with the detent, the latter's engagement with the stop 45a, while opening the switch 65, prevents closure of the receiver control switch consisting of the contact spring 63 and bridging elements 64.

The invention having been described, what is claimed as new and useful is:

1. Means for tuning a radio receiver to a selected frequency comprising a rotary element for effecting tuning of the receiver, a time mechanism, a disk positively driven by the time mechanism but provided with axial adjusting means to release the driving connection, driving means for the rotary element, a plurality of controls for the rotary element driving means, a plurality of pins mounted in the disk for axial movement therein and arranged in a plurality of concentric circular series, plungers for the manual adjustment of the pins when the disk is released from its driving connection with the time mechanism, the adjusted pins engaging the controls when the disk has its driving connection with the time mechanism re-established, the disk being of laminar form and the pins extending through all of the laminae, the intermediate lamina being of compressible material for frictional peripheral binding engagement with the pins.
2. Means for tuning a radio receiver to a selected frequency comprising a rotary element for effecting tuning of the receiver, driving means for said rotary element, a time mechanism, a member positively driven by the time mechanism, a detent, stops carried by the rotary element and selectively positionable at different points on the same, the detent being engageable with and disengageable from said stops, means for actuating said detent, a plurality of control means, and elements carried by said member and selectively adjustable thereon to periodically engage and actuate said controls, the detent actuating means comprising axially aligned solenoids having a common core operatively connected with the detent.
3. Means for tuning a radio receiver to a selected frequency comprising a rotary element for effecting tuning of the receiver, driving means for said rotary element, a time mechanism, a member positively driven by the time mechanism, a detent, stops carried by the rotary element and selectively positionable at different points on the same, the detent being engageable with and disengageable from said stops, means for actuating said detent, a plurality of control means, and elements carried by said member and selectively adjustable thereon to periodically engage and actuate said controls, the rotary element driving means comprising a pair of solenoids, sheaves carried by the rotary element, and flexible members trained over the sheaves in opposite directions and terminally connected one to the core of each of the solenoids.
4. Means for tuning a radio receiver to a selected frequency comprising a rotary element for effecting tuning of the receiver, electrical driving means for the rotary element, a time mechanism, a member positively driven by the time mechanism, a detent for the rotary element, electrical actuating means for the detent, a plurality of

control switches for controlling the rotary element driving means and the detent actuating means, and elements carried by said member and selectively adjustable in the latter to periodically engage and actuate said switches, the rotary element being provided with a multiple pole switch and the detent actuating means being in part controlled by the same, and the time mechanism having a control switch yieldingly held in closed position but tripped to open position after a specified time of movement of the time mechanism.

5. Means for tuning a radio receiver to a selected frequency comprising a rotary element for effecting tuning of the receiver and carrying a disk provided with spaced stops, a pivotally mounted detent engageable with said stop to retain the rotary element in any one of several predetermined positions, a time mechanism, a member positively driven by the time mechanism, driving means for the rotary element to rotate it in either direction, a pair of axially aligned solenoids having a common core operatively connected with the detent, switches controlling the driving means and the detent solenoids, and means carried by said member for periodically actuating said switches.

6. Means for tuning a radio receiver to a selected frequency comprising a rotary element for effecting tuning of the receiver, a time mechanism, driving means for the rotary element, a plurality of controls for the driving means, a disk, a plurality of pins carried by the disk and arranged in a circular series around its axis of rotation, said pins being selectively adjustable in the disk to engage and operate any of said controls, operative connections between the disk and the time mechanism to positively drive the former in timed relation with the latter and embodying a clutch, and means for axially moving the disk to release the clutch and rotate the disk independently of the time mechanism for selectively adjusting the pins, the clutch elements being engageable to effect clutching action only in one position of the disk with respect to the time mechanism.

7. Means for tuning a radio receiver to a selected frequency comprising a rotary element for effecting tuning of the receiver, a time mechanism, driving means for the rotary element, a plurality of controls for the driving means, a disk, a plurality of pins carried by the disk and arranged in a circular series around its axis of rotation, said pins being selectively adjustable in the disk to engage and operate any of said controls, operative connections between the disk and the time mechanism to positively drive the former in timed relation with the latter and embodying a clutch, and means for axially moving the disk to release the clutch and rotate the disk independently of the time mechanism for selectively adjusting the pins, the clutch comprising a gear positively driven by the time mechanism and a yoke fixed with respect to the disk and formed with arms arranged diametrically of the latter but of different radial extent and formed with inturned terminals entering openings in said gear spaced in correspondence to the spacing of said terminals.

8. Means for tuning a radio receiver to a selected frequency comprising a rotary element for effecting tuning of the receiver, a time mechanism, a member positively driven by the time mechanism, driving means for the rotary ele-

ment, a disk carried by the rotary element and formed with series of uniformly spaced holes therearound, stops positioned on said disk and selectively mountable at any corresponding points in said series of holes, a detent engageable with said stops to limit the movement of the rotary element to the points of positioning of the stops, means for releasing and engaging the detent with said stops, and a plurality of controls for the rotary element driving means and detent releasing and engaging means comprising a single member carried by the disk and a plurality of fixed stationary members arranged around the disk in accordance with the spacing of the stops to be engaged by the disk carried member, the member driven by the time mechanism having elements adjustable to periodically engage and operate said controls.

9. Means for tuning a radio receiver to a selected frequency comprising a rotary element for effecting tuning of the receiver, a time mechanism, a member positively driven by the time mechanism, driving means for the rotary element, a disk carried by the rotary element and formed with series of uniformly spaced holes therearound, stops positioned on said disk and selectively mountable at any corresponding points in said series of holes, a detent engageable with said stops to limit the movement of the rotary element to the points of positioning of the stops, means for releasing and engaging the detent with said stops, and a plurality of controls for the rotary element driving means and detent releasing and engaging means comprising a pin having a swivel mounting on said disk, a spring retaining the pin radially of the disk but permitting its movement laterally to either side of the radial line and a plurality of fixed stationary members arranged around the disk in accordance with the spacing of the stops to be engaged by said swivelly mounted pin, the member driven by the time mechanism having elements adjustable to periodically engage and operate said controls.

10. Means for tuning a radio receiver to a selected frequency comprising a rotary element for effecting tuning of the receiver, a time mechanism, a member positively driven by the time mechanism, driving means for the rotary element, a disk carried by the rotary element and formed with series of uniformly spaced holes therearound, stops positioned on said disk and selectively mountable at any corresponding points in said series of holes, a detent engageable with said stops to limit the movement of the rotary element to the points of positioning of the stops, means for releasing and engaging the detent with said stops and a plurality of controls for the rotary element driving means and detent releasing and engaging means comprising a laterally swingable member carried by said disk, a fixed arcuate rack carried at the periphery of said disk but concentric with the latter and a plurality of radially arranged pins carried by said rack and spaced on the same in accordance with the spacing of the stops to be engaged by said laterally swingable member, the member driven by the time mechanism having elements adjustable to periodically engage and operate said controls.

11. Means for tuning a radio receiver to a selected frequency comprising a rotary element for effecting tuning of the receiver, a time mechanism, a member positively driven by the time mechanism, driving means for the rotary element, a disk carried by the rotary element and formed with series of uniformly spaced holes

therearound, stops positioned on said disk and selectively mountable at any corresponding points in said series of holes, a detent engageable with said stops to limit the movement of the rotary element to the points of positioning of the stops, means for releasing and engaging the detent with said stops, and a plurality of controls for the rotary element driving means and detent releasing and engaging means comprising a plate 5 carried by the disk, a post having a swivel mounting in the plate at one end, a pin extending diametrically through the post, a spring tensioned 10

between the pin and the remote end of the plate for yieldingly retaining the pin laterally of the plate, an arcuate rack adjacent the periphery of the disk, and a plurality of radially arranged pins carried by the rack in accordance with the spacing of the stops to be engaged by the disk carried pin, the member driven by the time mechanism having elements adjustable to periodically engage and operate said controls. 5
